UNITED STATES PATENT OFFICE.

CARLETON ELLIS, OF NEW YORK, N. Y., ASSIGNOR TO COMBUSTION UTILITIES COMPANY, OF NEW YORK, N. Y., A CORPORATION OF NEW YORK.

APPARATUS FOR MANUFACTURING CEMENT.

No. 817,163.

Specification of Letters Patent.

Patented April 10, 1906.

Application filed February 3, 1903. Serial No. 244,027.

To all whom it may concern:

Be it known that I, CARLETON ELLIS, a citizen of the United States, and a resident of New York city, in the county of New York and State of New York, have invented certain new and useful Improvements in Apparatus for Manufacturing Cement, of which the following is a specification.

This invention relates to the burning of cement by means of producer-gas.

Methods embodying the use of producer-gas as a fuel have been tried from time to time, but have proved unsuccessful. Powdered fuel in spite of its many disadvantages has been found the only satisfactory fuel up to the present time for burning cement in rotary kilns. The large and expensive equipment required for drying and grinding the coal and the complicated system needed for handling and delivering this fuel to the kilns, together with the dangers from spontaneous combustion and from explosions due to the ignition of accidental admixtures of the finely-divided coal with air, have placed a ban upon this fuel and have made substitutes for it desirable.

In the experiments which have been made with gaseous fuel the gas-producers have been operated by steam and the unavoidable fluctuations in the quality of the gas, together with the trouble attendant upon the clinkering and stopping of the producer, have made cement-burning by this method appear far from promising.

In order to burn cement by gas, I have found that it is necessary that the gas be of uniform quality and be supplied to the producer in a regular unvarying stream. I have also found that in order to get a desirable output of cement from the kiln the air requisite for the combustion of the gas should be heated before entering the kiln.

I have found steam-operated producers to be unsatisfactory for this purpose, for the reason that inherently they cannot produce gas of uniform quality nor of uniform volume. The effect of these fluctuations in the gas is to cause the kiln to work erratically. If there be a temporary slight reduction in the temperature of a rotary cement-kiln, due to changes in the quantity or quality of fuel, the kiln receives a setback, from which it recovers very slowly. If, finally, through the

application of good gas for a considerable period of time the kiln is restored to its former good working condition, it is found with a steam-operated producer that such a condition is only transient, for fluctuations in the gas are liable to occur at any time, and the setback so received tends to maintain the kiln in poor working condition for the greater part of the time.

It is the object of this invention to provide a gas-producer and other accessories for the burning of cement which do away with the disadvantages above mentioned. For this purpose I preferably use the gas-generating system described in the copending applications Serial Nos. 228,915 and 233,800, with this modification, namely, that with the abnormal amount of carbon dioxid obtainable in a combined combustion calcination process of this character it is possible to introduce air slightly preheated into the producer-blast. The products of combustion used in the temperature regulation of the producer are considerably cooled through the contact with the cold entering raw material in the upper part of the kiln. Furthermore, they contain an unusually large amount of carbon dioxid, and these two factors together permit of a regulation of the producer temperature and of the consequent production of uniform gas.

I find that the gas obtained from this producer is dry—that is to say, the gas contains little or no free steam or steam-forming elements—and I find this anhydrous condition of the gas to be desirable for the burning of cement. The gas-producer is operated and regulated through the agency of products of combustion and decomposition taken from the stack or feed end of the kiln and returned by means of a fan or other mechanical draft appliance to the lower part of the gas-producer. The combustible gas formed by the passage of carbon dioxid and oxygen contained in this gaseous mixture through the bed of fuel is delivered to the cement-kiln through a suitable conduit. The air supplied to the kiln for combustion is preferably preheated, and I am able to heat this air in various ways. A stove or recuperator of the continuous type may be placed in the stack or dust-chamber at the head of the kiln, and air may be drawn therethrough and brought

through insulated pipes or underground conduits back to the discharge end of the kiln. In the hot clinker itself there is an appreciable amount of heat, which is capable of utilization, and where the arrangement of the plant is such that this is feasible I draw a portion of the air necessary for combustion through or over the hot clinker as it discharges from the kiln or after it has been deposited in the cooling device employed, and thus preheat the air to some extent in this manner. Another method of preheating the air is to employ a stove at the discharge end of the kiln near the gas-producer and to carry a slow coal fire in said stove, whereby the air which is drawn through is heated to the proper degree for developing rapid and intense combustion in the kiln.

When the percentage of carbon dioxid arising from combustion and from decomposition of carbonate of lime runs high in the stack-gases, it is possible to introduce the products of combustion into the gas-producer without previously cooling these entering gases other than that cooling to which they have been subjected in the upper portion of the kiln, and it is even, in fact, under these conditions possible to mix with the products of combustion a certain amount of air preheated by any of the methods hereinbefore described.

To effect the proper utilization of the heat in the waste gases, it is sometimes desirable, especially in case the rotary kilns employed are of considerable length, to alternate their relative positions and to thus have a stack of one kiln alongside of the clinker-discharge end of an adjoining kiln. It is thus practicable to make use of the heat in the stack-gas through the aid of a continuous recuperator or a regenerator of any suitable type. The nearness of the stack of one kiln to the discharge end of the other, and consequently to the gas-producer operating the latter, makes it possible to immediately utilize the sensible heat imparted to the air while passing through the recuperator and to thus lose very little of its sensible heat. Unless this arrangement be employed, there is a considerable loss of heat in the transmission of air, preheated at the stack, through a long pipe or conduit to the clinker-discharge end of the kiln. Such an alternation in the relative positions of the individual kilns allows of one-half of the coolers and gas-producers to be installed at one end of the rotary-kiln battery, the remainder to be placed at the other end, thus economizing in space and ease of operation.

In the accompanying diagrammatic drawing, which depicts a plan view of the apparatus, 1 and 1' represent rotary cement-kilns of the usual type—that is to say, a cylinder of iron or steel lined with fire-brick or other refractory material. At one end of the cylind-

er are situated the stacks 2 and 2', through which the products of combustion escape.

3 and 3' are clinker-pits beneath the lower or discharge end of kilns 1 and 1', into which the clinker discharges through the opening 35 and 35'.

4 and 4' are gas-producers of any suitable type discharging their gaseous combustible through conduits 5 and 5' into the lower part of their respective kilns. A gate (shown at 6 and 6') is a desirable addition to these conduits as a means for regulating the flow of the gas. The upper ends of the kilns are covered by the housings 7 and 7'. In these housings and stacks are located a series of pipes 8 and 8', through which cold air is drawn, and thereby heated by the waste products of combustion passing around aforesaid pipes. 9 and 9' are conveyers for delivering the raw material to the upper part of the kiln. Pipes 10 and 10' are connected with the stoves 8 and 8' and with the fan 11. Adjustable gates are shown at 12 and 12'. The fan 11 is used for forcing air through the preheating-pipes 8 and 8'. Pipes 14 and 14' enter the stacks at 13 and 13' and are connected to the fan 16' and 16, respectively, said pipes having adjustable valves 15 and 15'. The fans 16' and 16 draw products of combustion from stacks 2 and 2' and deliver these gases to the producer 4' and 4 at 19' and 19 through pipes 17' and 17. Gates 18' and 18 regulate the flow of gases. 20 and 20' are heating-stoves, which are shown diagrammatically in the drawings, as their construction need be of no particular design, and almost any form of pre-heating-stove now known to the art may be used for this purpose. Such a stove may be simply made of a series of pipes through which the air may be passed, these pipes being situated over a grate in which a fire is maintained and the products of combustion from which may be taken, if desired, by means of pipes 30 or 30' to the fan 16 to 16', respectively, and regulation may be made by means of the valves 31 and 31'. A connection with the clinker-pits 3 and 3' is shown at 32 and 32', respectively, also pipes 33 and 33', extending therefrom to the fan 16 and 16', whereby air may be drawn over the clinker as it is discharged from the kiln, and the air may thus to some extent be heated preparatory to its passage to the gas-producers or directly to the kiln itself, although connections in this drawing are not shown for the purpose. If heated air from this source is desired at 27 and 27', connections may be made from 32 and 32' to the suction-inlet of fan 11. On the gas-producers 4 and 4' are shown the steam-blowers 36 and 36', by means of which the producer may be operated by a steam-jet when through accident or otherwise the fans are disabled or when for some cause sufficient carbon dioxid cannot be obtained from the gases of the stack 130

to depress the temperature of the gas-producer to the desired non-clinkering point. Means for rotating the kilns 1 and 1' are shown at 37 and 37', respectively.

5 My method of operation is as follows: The calcareous or cement-forming material is delivered by the feeding devices 9 and 9' to the upper ends of the kilns 1 and 1', and by the rotation given to the kiln by the power applied at 37 and 37' the material is caused to move slowly down the length of the kilns and to come in contact with the flame produced by the combustion of the gas in the lower part of the kiln. The cement so formed discharges at the lower end of the kiln into a clinker pit or cooler or any other receptacle, such as is shown at 3 and 3', from which it may be taken by means of elevator to storage-bins or elsewhere. The fan 11 draws in 10 fresh air and impels it through pipes 10 and 10' to the stack-heating stoves 8 and 8', and this air after traversing the various pipes of aforesaid stoves becomes highly heated and passes through the pipe 21' and 21 and 15 through pipes 26 and 26' to the lower part of the kilns 1 and 1', respectively. If the degree of heat obtained by passing through the stack-heating stoves is not sufficient to give 20 the desired intensity of combustion needed 25 to produce the proper clinkering temperature in the kiln, a slow fire may be started in stoves 20 and 20' in order that the air may be pre-heated still more, and the intensity of the fire carried in aforesaid stoves 20 and 20' will 30 determine the temperature of the kiln. When the stoves 20 and 20' are in operation, pipes 30 and 30' serve to carry off the waste products of combustion therefrom, although the connections shown are not essential to this 35 apparatus and the products of combustion from aforesaid stoves may be conducted to any convenient chimney for disposal. Products of combustion derived from the stack at 13 and 13' are carried by the fans 16' and 16 to the gas-producers 4' and 4, respectively, 45 and such air as is necessary to maintain combustion in the gas-producers is supplied, preferably, from the clinker-pit through pipes 33 and 33'. As the temperature of the producer 50 is a function not only of the temperature of the entering gaseous mixture, but also of its percentage of oxygen and carbon dioxid, it is necessary to carefully adjust the gates or valves 18, 18', 31, 31', 34, 34', 15, and 15', in so 55 far as these may be in use, in order to maintain the combustion of the producer at an effective operating temperature without causing serious troubles and stoppages through the formation of clinker. The combustible 60 gas from 4 and 4' passes through a large conduit 5 and 5' and mixes with the heated air delivered at 27 and 27'. A flame of great calorific value and having powerful radiant and heat-reverberating qualities is formed at 65 this point and fills the kiln with a long flame

having unusual clinkering and calcination properties. The cement is in this manner easily and cheaply burned.

The various means by which this invention can be carried out will be obvious to one skilled in the art. I have diagrammatically indicated well-known features of construction organized into an apparatus or plant adapted for the practice of my invention. I do not limit myself to the particular mode of application as herein described, as it is obvious that different arrangements of the piping, flues, and valves and of the preheating devices may be made without departing from the scope of this invention.

What I claim is—

1. A cement-making apparatus comprising a gas-fired kiln, a gas-producer, a valved pipe connection discharging waste kiln-gases into the producer in controlled amount, means for introducing controlled amounts of air into said pipe connection, a heating-stove, means for returning and burning in the kiln the gas produced in the producer, and means for feeding to the burning means air heated by waste kiln heat and further heated by the stove.

2. A cement-making apparatus comprising a gas-fired kiln, a gas-producer, a valved pipe connection discharging waste kiln-gases into the producer in controlled amounts, means for introducing regulated amounts of air into said pipe connection, a heating-stove, means for also introducing a regulated amount of products of combustion from the stove into the pipe connection, means for returning and burning in the kiln the gas produced in the producer, and means for feeding to the burning means air heated by waste kiln heat and also further heated by the stove.

3. A cement-making apparatus comprising a kiln, a chimney-stack, a gas-producer, a valved pipe connection between stack and producer discharging stack waste gases into the producer in controlled amounts, means for introducing regulated amounts of air into said pipe connection, means for returning and burning in the kiln the gas produced in the producer, an air-heater in the stack, and means for feeding to the burning means air heated in said heater.

4. A cement-making apparatus comprising a kiln, a chimney-stack, a gas-producer, a valved pipe connection between stack and producer discharging stack waste gases into the producer in controlled amount, means for introducing regulated amounts of air into said pipe connection, means for returning and burning in the kiln the gas produced in the producer, a heating-stove, an air-heater in the stack and means for feeding to the burning means air heated in the stack-heater and further heated in the stove.

5. A cement-making apparatus comprising a kiln, a chimney-stack, a gas-producer, a

4

valved pipe connection between the stack and producer discharging stack waste gases into the producer in controlled amount, means for introducing regulated amounts of air into said pipe connection, means for returning and burning in the kiln the gas produced in the producer, a heating-stove, means for also introducing products of combustion from said stove into the pipe connection, an air-heater in the stack, and means for feeding to the burning means air heated in the stack-heater and further heated in the stove.

6. A cement-making apparatus comprising a pair of inclined rotary kilns arranged side by side with the higher end of the one opposite the lower end of the other, a gas-producer for each kiln, valved pipe connections for feeding the waste gases of one kiln into the producer of the other kiln in controlled amounts, mechanical means for creating a flow through each pipe connection, means for introducing controlled amounts of air into each pipe connection, and means for returning and burning in each kiln the gas from its producer.

7. A cement-making apparatus comprising a pair of inclined rotary kilns arranged side by side with the higher end of the one opposite the lower end of the other, a gas-producer at the lower end of each kiln, a chimney-stack at the higher end of each kiln, pipe connections for introducing regulated amounts of waste gases from each stack into the oppo-

site producer, means for introducing regulated amounts of air into each pipe connection, means for returning and burning in each kiln the gas produced in its producer, and an air-heater in each stack delivering heated air to assist in the combustion of gas in the opposite kiln.

8. A cement-making apparatus comprising a pair of inclined rotary kilns arranged side by side with the higher end of the one opposite the lower end of the other, a gas-producer at the lower end of each kiln, a chimney-stack at the higher end of each kiln, pipe connections for introducing controlled amounts of waste gases from each stack into the opposite producer, means for introducing regulated amounts of air into each pipe connection, means for returning and burning in each kiln the gas produced in its producer, an air-heater in each stack, a heating-stove for each kiln, means for conveying the air heated in each stack through a stove and thence to the opposite kiln to assist in burning the gas, and means for introducing regulated amounts of the products of combustion from the stoves into the pipe connections.

Signed at New York city, in the county of New York and State of New York, this 1st day of February, A. D. 1905.

CARLETON ELLIS.
